FIG. 1.

FIG. 2.

FIG. 4.

FIG. 3.

FIG. 5.

FIG. 6.

FIG. 8.

FIG. 7.

FIG. 1 is a front perspective view of a recreational vehicle light showing my new design;

FIG. 2 is a rear perspective view of the light;

FIG. 3 is a side elevational view of the light;

FIG. 4 is a top plan view of the embodiment shown in the first three figures;

FIG. 5 is a front perspective view of another form of the recreational vehicle light showing my new design;

FIG. 6 is a rear perspective view of the species of the recreational vehicle light shown in FIG. 5;

FIG. 7 is a side elevational view of the species of the recreational vehicle light shown in FIG. 5; and

FIG. 8 is a top plan view on a reduced scale of the embodiment of the invention shown in FIGS. 5 through 7.

The stippling is omitted in FIGS. 4 and 8 for con-

venience of illustration, but is understood to be uniform over the surface of the lens as shown in FIGS. 1-3 and 5-7.

I claim:

The ornamental design for a recreational vehicle light, substantially as shown and described.
